(57) **ABSTRACT**

A thin pump includes a casing, a rotor, and a stator. The casing has a bottom surface, an outer surface, a lower chamber, an upper chamber, an inlet channel, and an outlet channel. The outer surface is connected to the bottom surface. The upper chamber and the lower chamber connected to each other are surrounded by the outer surface. The upper chamber is located further away from the bottom surface than the lower chamber. The inlet channel and the outlet channel are located on the outer surface. The inlet channel and the outlet channel are respectively connected to the upper chamber and the lower chamber. The rotor includes an impeller rotatably disposed in the lower chamber and a magnetic component disposed on the impeller. The stator disposed in the casing corresponds to the magnetic component so as to drive the rotor to rotate with respect to the casing.

**CROSS-REFERENCE TO RELATED
APPLICATIONS**

This non-provisional application claims priority under 35 U.S.C. § 119(a) on Patent Application No(s). 109111160 filed in Taiwan, R.O.C. on Apr. 1, 2020, the entire contents of which are hereby incorporated by reference.

TECHNICAL FIELD

The present disclosure relates to a pump, more particularly to a thin pump.

BACKGROUND

As computer technology progresses, computer system can provide higher performance and, hence, more heat than lower performance devices. In order to prevent an overly high working temperature to damage internal electronic/electronic components, there is provided a passive heat exchanger, such as a heatsink, for absorbing heat generated by the electronic/electronic components. However, the heat dissipation efficiency of the heatsinks are very limited and sometimes not sufficient to catch the heat dissipation requirement of the electronic components nowadays. An alternative option is a liquid-cooling system. The liquid-cooling system is known for having a better heat dissipation performance than heatsink. A typical liquid-cooling system may include a radiator, a liquid plate, and a pump, where the radiator and the liquid plate are connected to each other, and the working fluid is pumped through the radiator and the liquid plate by the pump to form a circulation. The liquid plate can be mounted on a heat source (e.g., processor), the working fluid flowing through the liquid plate can absorb heat generated from the heat source and can be pumped to the radiator for heat dissipation.

In recent years, in order to satisfy demands for lightweight and small, designs of electronic products are developed toward being light, thin, short, and small. Some manufacturers believed that to reduce the size of the pump is a solution to make the electronic products become thinner, however, in fact, the typical small-sized pumps are unable to offer sufficient hydraulic head to maintain the original function. In other words, a pump that has sufficient hydraulic head is, typically, large in size and therefore does not fit the trend. Therefore, how to make a balance between small size and performance of pump is an important topic in the field.

SUMMARY

The present disclosure provides a thin pump in a small size while capable of providing a required performance.

According to one aspect of the present disclosure, a thin pump includes a casing, a rotor, and a stator. The casing has a bottom surface, an outer surface, a lower chamber, an upper chamber, an inlet channel, and an outlet channel. The outer surface is connected to the bottom surface. The upper chamber and the lower chamber are connected to each other and are surrounded by the outer surface. The upper chamber is located further away from the bottom surface than the lower chamber. One end of the inlet channel and one end of the outlet channel are located on the outer surface. The inlet channel is connected to the upper chamber, and the outlet channel is connected to the lower chamber. The rotor includes an impeller and a magnetic component. The impel-

ler is rotatably disposed in the lower chamber of the casing. The magnetic component is disposed on the impeller. The stator is disposed in the casing. The stator corresponds to the magnetic component of the rotor so as to drive the rotor to rotate with respect to the casing.

According to the thin pump discussed above, since the inlet channel and the outlet channel are located on the outer surface instead of located on the top surface or the bottom surface; that is, the inlet channel and the outlet channel are located at radial sides instead of located at axial sides of the impeller. As such, the thickness of the thin pump along the rotation axis of the rotor has no need to consider the inlet channel and the outlet channel and thus can be designed to be small.

BRIEF DESCRIPTION OF THE DRAWINGS

The present disclosure will become more fully understood from the detailed description given hereinbelow and the accompanying drawings which are given by way of illustration only and thus are not intending to limit the present disclosure and wherein:

FIG. 1 is a perspective view of a thin pump according to one embodiment of the present disclosure;

FIG. 2 is an exploded view of the thin pump in FIG. 1; FIG. 3 is a top view of the thin pump in FIG. 1;

FIG. 4 is a cross-sectional view of the thin pump taken along a line 4-4 in FIG. 3;

FIG. 5 is a partially enlarged view of the thin pump in FIG. 4;

FIG. 6 is a side view of the thin pump in FIG. 1; and

FIG. 7 is a cross-sectional view of the thin pump taken along a line 7-7 in FIG. 6.

DETAILED DESCRIPTION

In the following detailed description, for purposes of explanation, numerous specific details are set forth in order to provide a thorough understanding of the disclosed embodiments. It will be apparent, however, that one or more embodiments may be practiced without these specific details. In other instances, well-known structures and devices are schematically shown in order to simplify the drawing.

Please refer to FIG. 1 to FIG. 4, where FIG. 1 is a perspective view of a thin pump according to one embodiment of the present disclosure, FIG. 2 is an exploded view of the thin pump in FIG. 1, FIG. 3 is a top view of the thin pump in FIG. 1, and FIG. 4 is a cross-sectional view of the thin pump taken along a line 4-4 in FIG. 3.

As shown in FIG. 1 and FIG. 2, this embodiment provides a thin pump 10 including a casing 100, a rotor 200, and a stator 300. In addition, the thin pump 10 further includes a shaft 400, two washers 500, and a seal ring 600.

As shown in FIG. 2 and FIG. 4, the casing 100 includes a bottom part 110, a top part 120, and a cover 130. The top part 120 is disposed on the bottom part 110, and the seal ring 600 is located between and clamped by the bottom part 110 and the top part 120 so as to seal the gap between the bottom part 110 and the top part 120. The top part 120 and the bottom part 110 form a lower chamber Sd therebetween. The bottom part 110 has a bottom surface 111, and the top part 120 has a bottom surface 121, an outer surface 122, and a top surface 123. The bottom surface 121 of the top part 120 and the bottom surface 111 of the bottom part 110 are substantially coplanar. The top surface 123 of the top part 120 faces away from the bottom surface 121 of the top part 120. The

outer surface 122 of the top part 120 is located between the top surface 123 of the top part 120 and the bottom surface 121 of the top part 120. Two opposite sides of the outer surface 122 are respectively connected to an edge of the bottom surface 121 of the top part 120 and an edge of the top surface 123 of the top part 120. The outer surface 122 surrounds the lower chamber Sd.

In addition, the top part 120 has an upper chamber Su, a plurality of through holes O, an inlet channel Si, a ramp St, and an outlet channel So. The upper chamber Su is surrounded by the outer surface 122. The upper chamber Su is located further away from the bottom surface 121 of the top part 120 than the lower chamber Sd. The upper chamber Su and the lower chamber Sd are connected via the through holes O. One end of the inlet channel Si is located on the outer surface 122 of the top part 120, and the inlet channel Si is served as an inlet for a working fluid. The ramp St has a first portion St1, a second portion St2, and a middle portion St3. The first portion St1 is connected to the second portion St2 via the middle portion St3. The first portion St1 of the ramp St is connected to the inlet channel Si, and the second portion St2 of the ramp St is connected to the upper chamber Su. That is, the inlet channel Si is connected to the upper chamber Su via the ramp St. The working fluid is allowed to flow into the inlet channel Si and flow to the upper chamber Su via the first portion St1, the middle portion St3, and the second portion St2 of the ramp St.

A first surface St11 of the first portion St1 of the ramp St is located closer to the bottom surface 121 of the top part 120 than a second surface St21 of the second portion St2 of the ramp St. As shown in FIG. 4, a distance D1 between the first surface St11 and the bottom surface 121 is less than a distance D2 between the second surface St21 and the bottom surface 121 in a direction (not shown, parallel to a rotation axis AA of the rotor 200 shown in FIG. 4). The first surface St11 is connected to the second surface St21 via a curved surface St31 of the middle portion St3. In this embodiment, the curved surface St31 is, for example, a convex surface. In addition, a side of the curved surface St31 connected to the first surface St11 has a relatively steep slope, and the other side of the curved surface St31 connected to the second surface St21 has a relatively gentle slope; however, the present disclosure is not limited thereto. In some embodiments, the curved surface may have the same slope. In some other embodiments, the side of the curved surface connected to the first surface may have a relatively gentle slope, and the other side of the curved surface connected to the second surface may have a relatively steep slope. In still some other embodiments, the curved surface may be a concave surface. In further still some other embodiments, the middle portion may have an inclined surface that is a flat surface instead of the curved surface.

In this embodiment, the quantity of the through holes O of the top part 120 are plural, but the present disclosure is not limited thereto. In some embodiments, the top part 120 may have only one through hole O.

As shown in FIG. 3, a width W1 of the first portion St1 of the ramp St is smaller than a width W2 of the second portion St2 of the ramp St, but the present disclosure is not limited thereto. In some embodiments, the width of the first portion of the ramp may be greater than or equal to the width of the second portion of the ramp.

One end of the outlet channel So is located on the outer surface 122. The outlet channel So is connected to the lower chamber Sd, such that the working fluid in the lower chamber Sd can flow out of the thin pump 10 via the outlet channel So.

As shown in FIG. 4, the upper chamber Su connected to the second surface St21 is located close to the top surface 123 of the top part 120, and the inlet channel Si connected to the first surface St11 is located close to the bottom surface 121 of the top part 120. Therefore, the ramp St may have a sufficient height difference between the first surface St11 and the second surface St21. In such case, a center line C1 of the inlet channel Si is located closer to the bottom surface 121 than a center line C2 of the outlet channel So. However, the present disclosure is not limited thereto. In some embodiments, the center line of the inlet channel may be located further away from the bottom surface than the center line of the outlet channel. In some other embodiments, the center line of the inlet channel may be located at the same level as the center line of the outlet channel.

In addition, in this embodiment, one end of the inlet channel Si and one end of the outlet channel So are respectively located at two opposite sides of the outer surface 122, but the present disclosure is not limited thereto. In some embodiments, one end of the inlet channel and one end of the outlet channel may be respectively located at two adjacent sides of the outer surface.

The cover 130 is disposed on the top surface 123 of the top part 120 via, for example, adhesive. The cover 130 is able to cover the upper chamber Su and the ramp St.

The shaft 400 and the rotor 200 are located in the lower chamber Sd. The shaft 400 is fixed between the bottom part 110 and the top part 120 of the casing 100. The rotor 200 includes an impeller 210, a magnetic component 220, and an iron plate 230. The impeller 210 is fixed on the shaft 400 so that the impeller is rotatably disposed in the casing 100. The magnetic component 220 is disposed on the impeller 210 via the iron plate 230. That is, the iron plate 230 is located between the impeller 210 and the magnetic component 220. The iron plate 230 is configured to reduce magnetic flux leakage so as to increase excitation efficiency.

The washers 500 are sleeved on the shaft 400 and are respectively located at two opposite sides of the impeller 210. The washers 500 are respectively clamped between the impeller 210 and the bottom part 110 and between the impeller 210 and the top part 120, such that the impeller 210, the bottom part 110, and the top part 120 are spaced apart from one another to prevent them from hitting each other during rotation of the impeller 210. In addition, the washers 500 has a wear resistance greater than the casing 100 and therefore can improve the durability and life span of the thin pump 10.

Please refer to FIG. 5, there is shown a partially enlarged view of the thin pump in FIG. 4. As shown, a plane where a top surface (not numbered) of the impeller 210 is located is angled at an angle θ_1 with respect to a plane where the top surface 123 is located, a plane tangential to the curved surface St31 is angled at an angle θ_2 with respect to the plane where the top surface 123 is located, and the angle θ_2 ranges between $(\theta_1+50\%) \theta_1$ and $(\theta_1-50\%) \theta_1$. For example, when the angle θ_1 is 10 degrees, the angle θ_2 ranges between 5 degrees and 15 degrees. However, the present disclosure is not limited to the range of the angle θ_2 . In some embodiments, the angle θ_2 may be greater than 0 degree and be less than or equal to 90 degrees.

Please refer to FIG. 4, the first portion St1 of the ramp St is connected to the inlet channel Si, and the second portion St2 of the ramp St extends towards a point (not numbered) where the rotation axis AA of the rotor 200 passes. In addition, the second surface St21 of the second portion St2 is located further away from the bottom surface 121 than the rotor 200. When the thin pump 10 is placed in a manner that

the bottom surface 121 faces a platform such as a table, the second surface St21 is located at a higher level than the rotor 200. As shown in FIG. 4, the distance D2 between the second surface St21 and the bottom surface 121 is greater than a distance D3 between a top surface (not numbered) of the rotor 200 and the bottom surface 121 in the direction (not shown, parallel to a rotation axis AA of the rotor 200 shown in FIG. 4).

The stator 300 is disposed in the casing 100. The stator 300 corresponds to the magnetic component 220 of the rotor 200 so as to drive the rotor 200 to rotate with respect to the casing 100. Specifically, the bottom part 110 has an accommodating space 112 which is a recess formed on the bottom surface 111. The stator 300 is located in the accommodating space 112. As shown in FIG. 4, the stator 300 is located at a side of the bottom part 110 away from the rotor 200 along the rotation axis AA of the rotor 200. In addition, a depth of the accommodating space 112 is slightly greater than a thickness of the stator 300, such that the stator 300 is prevented from protruding from the bottom surface 111 of the bottom part 110.

As shown in FIG. 4, the stator 300 has a lower surface 310 on a side thereof located close to the bottom surface 121. The impeller 210 has an upper surface 211 on a side thereof located away from the bottom surface 121. The center line C1 of the inlet channel Si is located between a plane where the lower surface 310 of the stator 300 is located and a plane where the upper surface 211 of the impeller 210 is located. The thickness of the inlet channel Si does not affect the total thickness of the thin pump 10.

Note that the position of the inlet channel Si is not restricted. In some embodiments, defining a base line L equidistant from the upper surface 211 and the lower surface 310, a distance between the center line C1 of the inlet channel Si and the base line L may be less than 5 percent of a distance between the upper surface 211 and the lower surface 310. In some other embodiments, the inlet channel may be located between a plane where the upper surface of the impeller is located and a plane where the bottom surface of the top part is located.

As shown in FIG. 3 and FIG. 4, the working fluid flows along a direction indicated by arrow F during the operation of the thin pump 10. In detail, the working fluid flows to the ramp St from the inlet channel Si and then flows over the ramp St to flow into the upper chamber Su, then the working fluid flows down to the impeller 210 accommodated in the lower chamber Sd via the through holes O, and then the working fluid is moved with the impeller 210 and forced to go out of the thin pump 10 from the outlet channel So.

In this embodiment, the inlet channel Si and the outlet channel So are located on the outer surface 122 instead of located on the top surface 123 or the bottom surface 121; that is, the inlet channel Si and the outlet channel So are located at radial sides instead of located at axial sides of the impeller 210. As such, the thickness of the thin pump 10 along the rotation axis AA of the rotor 200 has no need to consider the inlet channel Si and the outlet channel So and thus can be designed to be small. In addition, as mentioned, the working fluid flows along the ramp St, which can reduce the flow resistance of the working fluid to increase the driving efficiency of the thin pump 10. Furthermore, the working fluid flowing down to the impeller 210 from the upper chamber Su can create an impact force due to the height of the ramp St, and the centrifugal force generated by the rotation of the impeller 210 can pressure the working fluid in the lower chamber Sd. As the working fluid flows out of the thin pump 10 from the outlet channel So, the working

fluid is pressurized to have a hydraulic head the same as or greater than the conventional axial flow pump (e.g., more than 2 meters).

Note that the description of the location of the inlet channel Si is defined by the bottom surface 121 of the top part 120, but it can be also defined by the bottom surface 111 of the bottom part 110, since the bottom surface 121 of the top part 120 and the bottom surface 111 of the bottom part 110 are substantially coplanar. In some embodiments, the bottom surface of the top part and the bottom surface of the bottom part may not be coplanar. In such case, the one of the two bottom surfaces which is located further away from the top surface of the top part than the other one would be used to define and describe the location of the inlet channel.

Please refer to FIG. 6 and FIG. 7, where FIG. 6 is a side view of the thin pump in FIG. 1, and FIG. 7 is a cross-sectional view of the thin pump taken along a line 7-7 in FIG. 6. As shown in FIG. 7, the center line C2 of the outlet channel So is substantially perpendicular to a radial direction RR of the lower chamber Sd. That is, part of the outlet channel So connected to the lower chamber Sd has an edge substantially tangential to the outer edge (not numbered) of the lower chamber Sd. As such, the direction of the outlet channel So would substantially equal to the tangential velocity of part of the working fluid. This makes the driving efficiency of the thin pump 10 can be increased. However, the present disclosure is not limited thereto. In some embodiments, the center line C2 of the outlet channel may not be perpendicular to the radial direction of the lower chamber.

According to the thin pump discussed above, since the inlet channel and the outlet channel are located on the outer surface instead of located on the top surface or the bottom surface; that is, the inlet channel and the outlet channel are located at radial sides instead of located at axial sides of the impeller. As such, the thickness of the thin pump along the rotation axis of the rotor has no need to consider the inlet channel and the outlet channel and thus can be designed to be small. In addition, the working fluid flows along the ramp, which can reduce the flow resistance of the working fluid to increase the driving efficiency of the thin pump. Furthermore, the working fluid flowing down to the impeller from the upper chamber can create an impact force due to the height of the ramp, and the centrifugal force generated by the rotation of the impeller can pressure the working fluid in the lower chamber. As the working fluid flows out of the thin pump from the outlet channel, the working fluid is pressurized to have a hydraulic head the same as or greater than the conventional axial flow pump (e.g., more than 2 meters).

The embodiments are chosen and described in order to best explain the principles of the present disclosure and its practical applications, to thereby enable others skilled in the art best utilize the present disclosure and various embodiments with various modifications as are suited to the particular use being contemplated. It is intended that the scope of the present disclosure is defined by the following claims and their equivalents.

What is claimed is:

1. A thin pump, comprising:
a casing, having a bottom surface, an outer surface, a lower chamber, an upper chamber, an inlet channel, and an outlet channel, wherein the outer surface is connected to the bottom surface, the upper chamber and the lower chamber are connected to each other and are surrounded by the outer surface, the upper chamber is located further away from the bottom surface than the

lower chamber, one end of the inlet channel and one end of the outlet channel are located on the outer surface, the inlet channel is connected to the upper chamber, the outlet channel is connected to the lower chamber, and a center line of the inlet channel is located closer to the bottom surface than a center line of the outlet channel;

a rotor, comprising an impeller and a magnetic component, wherein the impeller is rotatably disposed in the lower chamber of the casing, and the magnetic component is disposed on the impeller; and
a stator, disposed in the casing, wherein the stator corresponds to the magnetic component of the rotor so as to drive the rotor to rotate with respect to the casing.

2. The thin pump according to claim 1, wherein the casing has a ramp, and the inlet channel is connected to the upper chamber via the ramp.

3. The thin pump according to claim 2, wherein the ramp has a first portion and a second portion opposite to each other, the first portion of the ramp is connected to the inlet channel, the second portion of the ramp is connected to the upper chamber, and a first surface of the first portion of the ramp is located closer to the bottom surface than a second surface of the second portion of the ramp.

4. The thin pump according to claim 3, wherein the ramp further has a middle portion located between and connected to the first portion and the second portion, and a curved surface of the middle portion is located between and connected to the first surface and the second surface.

5. The thin pump according to claim 4, wherein a plane where a top surface of the impeller is located is angled at an angle θ_1 with respect to a plane where a top surface of the casing is located, a plane tangential to the curved surface is angled at an angle θ_2 with respect to the plane where the top surface of the casing is located, and the angle θ_2 ranges between $(\theta_1+50\%\theta_1)$ and $(\theta_1-50\%\theta_1)$.

6. The thin pump according to claim 5, wherein the angle θ_2 is greater than 0 degrees, and the angle θ_2 is less than or equal to 90 degrees.

7. The thin pump according to claim 3, wherein the ramp further has a middle portion located between and connected to the first portion and the second portion, and an inclined surface of the middle portion is located between and connected to the first surface and the second surface.

8. The thin pump according to claim 7, wherein a plane where a top surface of the impeller is located is angled at an angle θ_1 with respect to a plane where a top surface of the casing is located, a plane where the inclined surface is located is angled at an angle θ_2 with respect to the plane where the top surface of the casing is located, and the angle θ_2 ranges between $(\theta_1+50\%\theta_1)$ and $(\theta_1-50\%\theta_1)$.

9. The thin pump according to claim 8, wherein the angle θ_2 is greater than 0 degrees, and the angle θ_2 is less than or equal to 90 degrees.

10. The thin pump according to claim 3, wherein the second surface is located further away from the bottom surface than the rotor.

11. The thin pump according to claim 3, wherein a width of the first portion of the ramp is smaller than a width of the second portion of the ramp.

12. The thin pump according to claim 2, wherein the casing comprises a bottom part, a top part, and a cover, the top part is disposed on the bottom part, the top part and the

bottom part form the lower chamber therebetween, the upper chamber and the ramp are located at a side of the top part away from the lower chamber, the top part has at least one through hole connected to the upper chamber and the lower chamber, and the cover is disposed on the top part to cover the upper chamber and the ramp.

13. The thin pump according to claim 12, wherein the bottom surface and the outer surface are located on the top part.

14. The thin pump according to claim 12, wherein the bottom surface is located on the bottom part, and the outer surface is located on the top part.

15. The thin pump according to claim 12, wherein the bottom part has an accommodating space, and the stator is located in the accommodating space.

16. The thin pump according to claim 12, further comprising a seal ring, wherein the seal ring is located between and clamped by the bottom part and the top part.

17. The thin pump according to claim 2, wherein the ramp has one end connected to the inlet channel and another end extending towards a point where a rotation axis of the impeller passes.

18. The thin pump according to claim 1, wherein the stator is located at a side of the casing away from the rotor along a rotation axis of the rotor.

19. The thin pump according to claim 1, wherein the inlet channel and the outlet channel are respectively located at two opposite sides of the outer surface.

20. The thin pump according to claim 1, wherein the inlet channel and the outlet channel are respectively located at different sides of the outer surface.

21. The thin pump according to claim 1, wherein the stator has a lower surface on a side thereof located close to the bottom surface, the impeller has an upper surface on a side thereof located away from the bottom surface, and the center line of the inlet channel is located between a plane where the lower surface of the stator is located and a plane where the upper surface of the impeller is located.

22. The thin pump according to claim 21, wherein a base line is defined to be equidistant from the upper surface and the lower surface, and a distance between the center line of the inlet channel and the base line is less than 5 percent of a distance between the upper surface and the lower surface.

23. The thin pump according to claim 1, wherein the impeller has an upper surface on a side thereof located away from the bottom surface, and the inlet channel is located between a plane where the upper surface of the impeller is located and a plane where the bottom surface is located.

24. The thin pump according to claim 1, further comprising a shaft and two washers, wherein the shaft is fixed in the casing, the impeller of the rotor is rotatably disposed on the shaft, and the washers are sleeved on the shaft and are respectively located at two opposite sides of the impeller.

25. The thin pump according to claim 1, wherein the center line of the outlet channel is substantially perpendicular to a radial direction of the lower chamber.

26. The thin pump according to claim 1, wherein the rotor further comprises an iron plate located between the impeller and the magnetic component.
